United States Patent Office

Des. 203,623
Patented Feb. 1, 1966

203,623

DENSITOMETER

Francesco Milani, Bellinzona, Tessin, Switzerland, assignor to Gretag Limited, a corporation of Switzerland

Filed May 15, 1964, Ser. No. 79,990

Claims priority, application Switzerland Nov. 18, 1963

Term of patent 7 years

(Cl. D52—6)

Fig. 2.

FIG. 1 is a front side perspective view of a densitometer showing my new design.

FIG. 2 is a top plan view thereof.

FIG. 3 is a back side elevational view thereof.

FIG. 4 is a bottom plan view thereof.

FIG. 5 is an end elevational view thereof.
The other end view of the densitometer is identical with the end shown in FIG. 5.

I claim:

The ornamental design for a densitometer, as shown and described.
